(57) CLAIM

The ornamental design for a rear of a purse, as shown and described.

DESCRIPTION

FIG. 1 is a rear view of a rear of a purse showing our invention; and,

FIG. 2 is a rear perspective view thereof.

The broken line showing of boundaries and the remainder of a purse is for illustrative purposes only and forms no part of the claimed design.

1 Claim, 1 Drawing Sheet
